UNITED STATES PATENT OFFICE

RUSSELL D. WELLS, OF POTTSTOWN, PENNSYLVANIA

COMBINATION RANGE

Application filed April 28, 1931. Serial No. 533,448.

The object of my present invention is to devise a novel construction of a combination range wherein the same baking oven can be employed for cooking with a solid fuel or with gas.

A further object of the invention is to devise novel means for mounting a burner in the bottom of the oven and novel means for providing the proper air for combustion.

A further object of the invention is to provide, in a device of this character, novel ventilating means whereby the proper ventilation of the baking or cooking chamber can be maintained.

With the above and other objects in view, as will hereinafter more clearly appear, my invention comprehends a novel combination range.

It further comprehends a novel combination range wherein a common baking and heating oven is provided which is adapted to be heated by the products of combustion passing from a fire or solid fuel, such as, for example, coal, wood, or coke, and also by means of a novel construction and arrangement of a gas burner mounted on the bottom plate of the oven.

Other novel features of construction and advantage will hereinafter clearly appear in the detailed description and the appended claims.

For the purpose of illustrating the invention, I have shown in the accompanying drawings a typical embodiment of it, which, in practice, will give satisfactory and reliable results. It is, however, to be understood that the various instrumentalities of which my invention consists can be variously arranged and organized, and my invention is not limited to the exact arrangement and organization of these instrumentalities as herein set forth.

Figure 1 is a perspective view of a combination range embodying my invention.

Figure 2 is a perspective view of a ventilating damper and its control in detached position.

Figure 3 is a section through the bottom of the oven.

Figure 4 is a top plan view of the construction seen in Figure 3.

Figure 5 is a sectional plan view, partly diagrammatic of the range.

Figure 6 is a sectional elevation, partly diagrammatic, of the combination range.

Figure 7 is a sectional elevation on line 7—7 of Figure 1, to bring out more particularly the manner in which the products of combustion pass around the oven and the channels for the feed of air to the gas burner.

Similar numerals of reference indicate corresponding parts.

Referring to the drawings:

My present invention enables one to employ, in conjunction with a range adapted for burning solid fuel, a gas burner which can be used to heat the same oven and which is constructed and arranged in a novel manner in order to provide for its ease of assembly, and durability, and also to provide the requisite air for combustion, as well as the proper ventilation of the oven when gas is being used as a fuel.

1 designates a combination range embodying my invention, which is provided with a baking and cooking oven 2. This baking and cooking oven 2 is adapted to be heated by means of the products of combustion passing from a coal, wood, coke, or equivalent fire 3, in the direction of the arrows, passing over the top of the oven through the passage 4 around the side of the oven through the passage 5 and across the bottom of the oven through the passage 6. The products of combustion then pass through the port 7 into the discharge passage formed by the flue 8. The products of combustion may pass directly from the fire to the flue 8 if the manually actuated damper 9 is in its open position to permit the air to pass through the conventional ports opening into the flue 8.

10 designates a valve controlled gas conduit which communicates with a gas burner 11 which is mounted within an open-ended casing 12. The bottom 13 of the oven is provided with a shoulder forming step 14 adapted to receive a casting 15 in the form of an annulus. This casting 15 is seated at its outer portion on the step 14 and at its

inner portion on a shoulder forming step 16 connected with a plate 17 in the form of a casting. An asbestos ring 18 is interposed between the ring shaped casting 15 and the 5 steps on which it is supported. The casting 15 is flush with the top face of the bottom plate 13 of the oven and is secured by means of fastening devices 19 with an auxiliary bottom plate 20 spaced from the bottom plate 10 13 and adapted to be received in the recess 21 in the casing 12.

The ring formed by the casting 15 is secured to the plate 17 by means of fastening devices 22, such as, for example, the stove bolts and nuts shown. The burner 11 is supported by means of a bar or plate 23 on which the burner 11 rests and this supporting member 23 is mounted on the threaded rods 24 which are provided with nuts 25 which retain the supporting member 23 against the spacing members 26 so that an air passage 27 is provided for the burner. The casing 12 forms a combustion chamber and is recessed at its upper end as at 28 to receive the 20 depending portion of the plate 17 which is centrally apertured as at 29. The plate is provided with a depressed seat 30 formed by an annular recess adapted to receive a cover 31 which is hinged to a bracket 32 hinged at 30 33 to the plate 17. The plate 17 is provided with the vent ports 34, preferably located on opposite sides of the passage 29. The air for combustion enters through the ports 35 in the back wall of the range.

35 The oven is provided with a ventilating damper 37 mounted in guides 38 and provided with ports 39 which control communication with the exit flue 8. This damper is manually controlled by means of a grasping 40 handle 40 connected with the slide damper 37 to move it into its opened or closed position. This damper and the ports which it controls is preferably located in the inner and upper left hand corner of the oven so that a 45 direct communication can be made with the exit flue 8.

The upper part of the range is provided with the gas heated top 41, the necessary gas burners being provided therefor, and it is 50 also provided with the coal heated top 42.

The manner in which the combination range is operated and controlled will now be apparent to those skilled in this art. Any desired type of solid fuel may be placed on 55 the grates 36, and if the slide damper 9 is in its opened position, the products of combustion will pass to the exit flue 8. If, however, the damper is closed then the products of combustion pass around the oven passing through 60 the port 7 into the exit flue 8. If it is desired to employ, in addition to the heat derived from the coal fire, heat from a gas burner, the cover or lid 31, which was before in its closed position, is now moved into its 65 opened position, seen in Figures 3 and 4, and

the gas burner 11 is lighted so that the common oven 2 is both externally and internally heated. When the portion of the range, adapted for solid fuel, is not being used, such as, for example, would occur in warm weather, the gas burner only is employed. The air for combustion enters through the air inlet ports 35 and passes through the passages 27 to the burner 11, thence through the outlet 29 of the casing 12.

When the oven is to be heated by gas the cover 31 is moved to uncover the aperture 29 and also the vent ports 34. The ventilating damper 37 is opened for a short period and then it is closed so that the oven is vented by the products of combustion passing through the vent ports 34 into the bottom passage 6 and thence through the port 7 into the discharge passage formed by the flue 8. When the stove is heated by solid fuel the usual draft door is employed for admitting air for primary combustion, and the cover 31 is closed thus closing the vent ports 34 so that the venting action takes place through the main ventilating ports controlled by the damper 37. If the range is used for burning only solid fuel, then the cover or lid 31 is closed on its seat 30.

My present construction and arrangement of gas burner in the bottom of the oven is constructed and arranged in such a manner that it can be economically manufactured and assembled and will not interfere with the operation of the range when solid fuel is being used.

It is also constructed in such a manner that 100 the buckling of the bottom of the oven is prevented.

It will now be apparent that I have devised a new and useful combination range which embodies the features of advantage enumerated as desirable in the statement of the invention and the above description, and while I have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

Having thus described my invention what I claim as new and desire to secure by Letters Patent, is:—

1. In a gas range, an oven having an aperture in its bottom, with the walls surrounding said bottom recessed, a ring seated in said recess, a central plate on which said ring is also seated, an auxiliary bottom member, a burner casing open at both ends between said plate and said bottom member, fastening devices between said ring and bottom member to secure the parts in assembled condition, said plate having vent ports opening through it above said casing to vent said oven, a gas burner supported in said casing, and a cover 125

hinged to said plate and covering said ports when closed.

2. In a gas range, an oven having its bottom wall apertured and recessed to form a seat, a burner plate also recessed to form a seat, a ring adapted to be received in said seats, sheet of fire resistant material between said ring and said seat, a burner casing engaging said burner plate, a bottom member supporting said casing and connected with said ring, a burner supported in said casing, said plate having means to vent products of combustion from said oven, and a cover closing the upper end of said casing and controlling said vent ports.

3. In a gas range, an oven having its bottom wall apertured and recessed to form a seat, a burner plate also recessed to form a seat, a ring adapted to be received in said seat, a sheet of fire resistant material between said ring and said seat, a burner casing engaging said burner plate, a bottom member supporting said casing and connected with said ring, a burner supported in said casing, said plate having vent ports through it and a depressed seat, a cover to engage said seat and close said vent ports, and a bracket hinged to said cover and to said burner plate.
